UNITED STATES PATENT OFFICE.

VIOLA FITZ, OF RICHMOND, INDIANA.

CRIB ATTACHMENT FOR BEDSTEADS.

SPECIFICATION forming part of Letters Patent No. 399,660, dated March 19, 1889.

Application filed August 24, 1887. Serial No. 247,734. (No model.)

To all whom it may concern:

Be it known that I, VIOLA FITZ, a citizen of the United States, residing at Richmond, in the county of Wayne and State of Indiana, have invented certain new and useful Improvements in Crib Attachments for Bedsteads; and I do hereby declare the following to be full, clear, and exact description of the invention, such as will enable others skilled in the art to which it appertains to make and use the same, reference being had to the accompanying drawings, and to letters or figures of reference marked thereon, which form a part of this specification.

15 My invention relates to certain new and useful improvements in crib attachments for bedsteads, and has for its object to furnish an attachment of this kind which can be readily attached to or detached from a bedstead; which can be used as a crib separately from the bedstead when so desired; which can be folded compactly together, so as to occupy but little space when not in use, and which may be lengthened, when desired, to adapt it 25 for use by larger children than could otherwise occupy the same; and the invention consists in the construction of the crib, substantially as hereinafter fully described, and as set forth in the claim.

30 In the accompanying drawings, Figure 1 is an elevation of the attachment, showing the manner of attaching it to the side rail of a bedstead, and showing in dotted lines one of the end sections swung down into a horizontal position. Fig. 2 is a transverse section taken through one of the hinge straps or leaves which serve to attach the crib to the bedstead. Fig. 3 is a detail isometric view, on an enlarged scale, of a portion of a side 35 and end section of the crib, showing the means for locking said sections together when in the position shown in Fig. 1.

A indicates the crib having the end sections, $a\ a$, side section, a' , and bottom a^2 .
45 B indicates the side rail of a bedstead with which the attachment is to be used, and to which side rail the crib is attached.

For the purpose of providing a support for the outer side of the crib, I provide legs b , 50 one at either end, and, to adapt the crib for use

separate from the bedstead, I provide two more of such legs upon the inner side thereof, as shown in Fig. 2. The end sections, $a\ a$, and side section, a' , and legs b of the crib I prefer to hinge or pivot to the side rails of 55 the bottom a^2 , whereby when the crib is not in use it may be detached from the bed and the end and side sections as well as the legs folded upon the bottom, so that the crib in its folded condition will occupy but a very small 60 space, and can be set away beneath the bedstead or elsewhere until further used.

To provide for the ready attachment of the crib to and its detachment from a bedstead, I employ the following means: Upon the rail 65 c , on the inner side of the crib and at either end, is provided a hinge-strap, d , one section or leaf of which is screwed to the rail c , while the other section or leaf is made longer and fits into a keeper, e , secured to the side rail, 70 B , of the bedstead.

The keepers e are secured upon the inner side of the rail B , so that when the leaves are fitted therein the rail c of the crib will then rest upon the upper edge of the side rail, B , 75 and thus serve to firmly support the inner side of the crib, in which arrangement the legs for supporting the inner side of the crib could obviously be dispensed with.

For locking the side and end sections of the 80 crib together when raised to the position shown in Fig. 1—that is to say, when the crib is to be used—any suitable means may be employed, though I prefer to use the means shown in Fig. 3, which consist of a slotted 85 plate, f , secured to the upper end of the end posts, a^3 , of the side section, a' , upon the inner side thereof, and a headed pin or lug, f^2 , projecting from the top rail of each of the end sections, $a\ a$, which pins or lugs will, when 90 the end sections are raised, enter the slot in the plates f , and thus serve to hold said end and side sections securely together.

I prefer to so hinge or pivot one or both of the end sections of the crib to the longitudinal rails of the bottom that it may be folded inward upon said bottom and outward therefrom, as shown in dotted lines, Fig. 1, and when in the latter position will be supported by the end cross-rails of the crib-bottom, 100

forming practically a continuation or extension of said bottom, and adapting the crib for use by larger children.

Having described my invention, what I claim is—

The combination of a crib having a complete set of supporting-legs pivoted thereto, leaves hinged to the side rail of said crib, and a bedstead provided with keepers on the inner side of the side rail thereof, whereby the

crib may be attached to and detached from the bedstead and used either in connection with or independently of the same, substantially as described.

In testimony whereof I affix my signature in presence of two witnesses.

VIOLA FITZ.
